UNITED STATES PATENT OFFICE

HARRY B. MASTERS, OF KEOKUK, IOWA

MILL

Application filed March 13, 1929. Serial No. 346,646.

This invention relates to grinding machines of the type known as "hammer mills"; and among other objects, the invention aims to increase the production of hammer mills and like machines particularly when used for grinding grains and other products which tend to cake or form doughy masses which clog the screen of the hammer mill.

In the accompanying drawing forming a part of this application,

Fig. 1 is an elevation of a hammer mill embodying the invention, parts being shown in vertical section so as to show the interior arrangement; and

Fig. 2 is a plan view of the three part suction line which leads from the lower or discharge side of the screen to the suction fan.

The grinding of certain grain by-products by commercial forms of hammer mills has given a great deal of trouble. The screen used should have a maximum mesh of $\frac{1}{16}$ inch, and in some instances could advantageously be smaller. When certain grain products are ground, the ground material will cake and completely fill the interstices of the screen, preventing outflow of the ground material and choking the machine with the material constantly being fed to the machine, necessitating shutting down the machine, taking out the screen and either cleaning it immediately or replacing it with another, and clearing away the spilled material.

Efforts to obviate at least partial caking of the screen (thus greatly lowering production) had been uniformly unsuccessful up to the time this invention was tried out. Larger fans, fans of different construction, higher fan velocities, larger suction lines, different types of screens and other expedients were resorted to; but the results were always failures. A machine which had been guaranteed by the manufacturer to handle 1200 lbs. of the material in one hour would deliver but 600 lbs. per hour and even then gave trouble. Frequently, it was found that about 90% of the ground material was passing through the relatively small central bottom area of the screen, the sides of the screen having become clogged and entirely ineffective.

According to the invention, the suction line is divided into at least two and preferably three parts or lines, all preferably leading to the usual suction fan mounted on the shaft of the hammer mill. This improvement has enabled the identical machine previously considered to be a failure, to handle continuously as high as 3600 lbs. per hour of the same material, an increase in production of some 600%, without any extra expenditure of power or other disadvantages.

Referring particularly to the drawing, there is shown a hammer mill comprising a housing 5 having an intake 6 through which the material to be ground is fed, a motor-driven shaft 7 to which the hammers 8 are connected, and a screen 9, semi-cylindrical in form. The parts described are all standard, but taken in combination with other elements to be described, form a part of the present invention.

Secured to the hammer mill is a casing 10 which serves as a sort of exhaust hood for the screen, being open to the suction side of the usual fan (not shown). In effect, the casing 10 is the lower half of the housing of the mill, and provides a suction chamber at the base of the machine. The casing 10 is divided by the re-entrant walls 11 into three parts, each providing a suction area 80 comprehending roughly one-third of the total effective screen area, and each being separate from the others. A suction pipe 12 leads from each part of casing 10 to a fan intake or suction pipe 13 whose diameter is several times that of one of the pipes 12, the three pipes preferably coming together at one point, as shown at 14. The three pipes 12 may be continued on the other side of the machine from the fan, as shown in Fig. 2, 90 and may have air intake valves 15, which will increase the effectiveness of the suction fan. Other air valves 16 may be provided at various high points in casing 11 to prevent the material from accumulating at times against 95 the upper part of the casing.

It will be understood that while Fig. 2 indicates that the fan suction line 13 is more or less in the same plane as the pipes 12, in practice the suction line 13 is usually V-100

shaped, being brought around to the suction fan (not shown) mounted on the shaft 7 of the hammer mill.

As improved results are obtained by using but two suction areas adjacent the screen, I believe I am entitled to claims broad enough to cover this less desirable arrangement, as well as the preferred construction shown in the drawing.

10 Obviously, the present invention is not restricted to the particular embodiment thereof herein shown and described.

What I claim is:—

15 1. In a mill, in combination, a screen; a power-driven shaft; disintegrating means revolved by the shaft adjacent said screen; a suction fan; and a suction discharge hopper between the discharge side of the screen and the fan, said suction discharge hopper being 20 divided into a plurality of adjacent compartments into which the material ground above the screen directly discharges.

25 2. A hammer mill or the like comprising, in combination, a screen; a power-driven shaft; a multiplicity of hammers revolved by the shaft adjacent said screen; a suction fan; and a suction hood between the discharge side of the screen and the fan, said suction hood being divided into three substantially equal parts or areas into which the material ground above the screen directly 30 discharges.

35 3. A hammer mill or the like comprising, in combination, a multiplicity of revolving hammers; a screen adjacent the path of movement of said hammers; a suction hood beneath the screen into which the ground material is directly discharged, said hood having one or more re-entrant portions to provide two or more sharply defined suction areas which together comprehend the entire screen; and separate pipes leading from said suction areas to a suction line.

40 45 4. A hammer mill or the like comprising, in combination, a multiplicity of revolving hammers; a screen adjacent the path of movement of said hammers; a suction hood below the screen and covering the entire lower part thereof; said hood receiving the ground material directly from the screen and having one or more partition walls extending to the screen; said partition walls separating the suction hood into two or more suction areas; and a suction pipe leading from said areas so as to conduct away material sucked through the screen.

50 55 60 5. A hammer mill or the like comprising, in combination, a multiplicity of revolving hammers; a screen adjacent the path of movement of said hammers; a suction hood beneath the screen having one or more re-entrant portions which extend in the direction of the shaft of the hammer mill to provide two or more sharply defined suction areas which together comprehend the entire

lower side of the screen; and separate pipes leading from said suction areas to a suction line of larger diameter.

6. A hammer mill or the like comprising, in combination, a multiplicity of revolving hammers; a screen adjacent the path of movement of said hammers; a suction hood below the screen and covering the entire lower part thereof; said hood receiving all the material ground on the opposite side of the screen and having one or more partition walls extending to the screen transversely thereof and separating the suction hood into two or more suction areas; and a suction pipe leading from each of said suction areas so as to conduct away material sucked through the screen.

7. A hammer mill or the like comprising, in combination, a multiplicity of revolving hammers; a cylindrical screen adjacent the path of movement of said hammers; a suction hood below and spaced from the screen covering the entire lower half thereof; said hood having two partition walls extending to the screen transversely thereof and providing three sharply defined separated suction areas on the suction side of the screen; the ground material passing through the screen directly into the suction areas aforesaid; three suction pipes leading from the respective suction areas; and a suction line of large diameter compared with said suction pipes having the longitudinal axis thereof lying in the same vertical plane with the middle suction pipe; the two outside suction pipes joining the suction line at the same point and being disposed symmetrically relative to the suction line.

8. A hammer mill or the like comprising, in combination, a multiplicity of revolving hammers; a cylindrical screen adjacent the path of movement of said hammer; a suction hood below and spaced from the screen and covering the entire lower half thereof; the ground material discharging directly into said hood; two partition walls inside the hood extending to the screen transversely thereof and providing three sharply defined separated suction pipes of equal area leading from the respective suction areas; and a suction line of large diameter compared with said suction pipes having the longitudinal axis thereof lying in the same vertical plane with the middle suction pipe; the suction line having a frusto-conical section where the middle suction pipe is joined to it and the two outside suction pipes joining the suction line at the frusto-conical section at diametrically opposite points.

9. In a hammer mill having revolving hammer means, a screen for separating fine from coarse material acted upon by said hammer means, and means for causing an air flow from within the mill outwardly through the screen to carry ground material therefrom,

the combination therewith of provisions for subdividing the screen into distinct areas and substantially equalizing the air flow through said areas.

- 5 10. A grinding mill having revolving hammers, a screen outside of the hammers, a chamber of which the screen forms one wall, means for exhausting air from said chamber, and partition means within the chamber
10 dividing the same into separate passages each in separate communication with a different area of the screen.

In testimony, that I claim the foregoing as my own, I have hereto affixed my signature.
